UNITED STATES PATENT OFFICE.

HORACE M. McDONALD, OF INDIANAPOLIS, INDIANA.

COMBINATION-LOCK.

No. 911,150.

Specification of Letters Patent.

Patented Feb. 2, 1909.

Application filed August 11, 1908. Serial No. 447,996.

To all whom it may concern:

Be it known that I, HORACE M. McDONALD, a citizen of the United States, residing at Indianapolis, in the county of Marion and 5 State of Indiana, have invented certain new and useful Improvements in Combination-Locks, of which the following is a specification.

This invention relates to improvements in 10 locks which are locked and unlocked without a key by the manipulation of combination plates, and the object of the invention is to provide a lock which will be simple, strong, and durable, and which will be constructed 15 with few parts or pieces, and which will be inexpensive to manufacture.

I accomplish the object by the mechanism illustrated in the accompanying drawing, in which—

20 Figure 1, is an edge view of my invention embodied in a pad-lock; Fig. 2 is a view in side elevation of the lock shown in Fig. 1; Fig. 3 a view in side elevation similar to Fig. 2 except that the near revolving plate is removed to show the inner mechanism of the lock and the far plate is broken away to show its retaining pin. Fig. 4 is a cross section on the line 4—4 of Fig. 2. Figs. 5, 6 and 7 represent the dismembered parts of my im- 25 proved lock in which Fig. 5 is a perspective view of the inner side of one of the revolving plates, Fig. 6 a radial section of the middle or annular drum with the link in maximum outward position and Fig. 7 an edge view of 30 the second revolving plate. Fig. 8 is a perspective view of a chest showing a modified form of my lock.

Like characters of reference indicate like parts throughout the several views.

40 Referring to the drawing, 10 represents the annular sleeve or case with which the other parts of the lock are assembled. It is a cylindrical drum and has its two ends closed by means of circular plates 11 and 12. The 45 plates 11 and 12 are duplicates of each other except as to the reverse position which they occupy when assembled in the drum 10 and the resulting reversal of the characters denoting the combination of the lock. A de- 50 scription of plate 11 will therefore suffice for plate 12, with the above explanation in mind. The largest diameter of plate 11 is approxi- 55 mately the same as the outside diameter of drum 10. This diameter is maintained for a width sufficient to permit the placing thereon of characters, here shown as numerals from 1

to 9 inclusive, for indicating a combination number which in this invention will comprise two digits, one for each of the two plates 11 and 12. The diameter of the plate 11 is reduced equal to the thickness of the walls of the drum 10 thereby forming a shoulder 13 and extension 14. The extension 14 projects into the drum 10 making a close working fit therein. The extension 14 is provided 60 with an annular groove 15 to receive the inner ends of retaining rivets 16. The rivets 16, here shown as three in number, are inserted through suitable holes in drum 10 and have their inner ends approximately in contact with the bottom of groove 15, to prevent the rivets being driven through the drum 10 into the lock to release the plate by those attempting to pick the lock.

The width of the drum 10 is such as to provide a space 17 between the two plates 11 and 12 when the plates and drums are assembled, as shown in Fig. 4. This space 17 is equal in width to the thickness of bar 18. The bar 18 is a part of the inverted 75 U-shaped link 20. The link enters the drum 10 through a suitable opening provided for that purpose in proper alignment with the space 17, and is provided adjacent to its inner end with the two opposing side lugs 22. 80 These lugs may be formed integral with the bar or may be the projecting ends of a pin seated in the end of the bar 18. The plates 11 and 12 are provided with radial grooves 85 23, one for each plate, extending from the periphery of extension 14 to the center of the inner face of the plate. The grooves 23 are just wide enough to make a close fit with lugs 22, and their depth is approximately 90 equal to the length or projection of the re- 95 spective lugs.

The ends of the links 20 are far enough away from the drum 10 when the link is in its maximum outer position to permit an end of the link to be passed through a staple, 100 or the like, with which the pad-lock is to be used. The bar 18 is then pushed in, carrying the link 20 with it. The ends of the link pass through suitable holes in the drum 10, into the position shown in Fig. 3, which prevents the withdrawal of the link from its staple. The inner ends of the grooves 23 are half-round, their curvature being described from the center of the circular extension 14, whereby, when the lugs 22 reach these half-round ends of the grooves they will be at the centers of the two plates and the latter will 105 110

be free to be rotated around said lugs. The periphery of the drum will be marked with a line 30, and the visible peripheries of the plates 11 and 12 will be provided with index 5 characters, here shown as numerals as already described, though letters or other characters could be employed. These numerals will be so placed with relation to the line 30, in the manufacture of the lock, that 10 a predetermined two of them when brought to the line will dispose their disks with their grooves 23 in proper position to allow the bar 18 to be moved outwardly to unlocked position. In the drawing, Fig. 1, the combination number is 75, which means that when plates 11 and 12 are rotated so as to bring the numeral 7 of plate 11 at one end of the line 30, and the numeral 5 of the plate 12 15 at the other end of said line, the grooves 22 of both plates will be in the position shown in Fig. 4. The grooves 23 are shown as entering the grooves 15 owing to the thinness of the outer flange member or extension 14 but this may be obviated if desired by 20 thickening the flange or reducing the depth of the groove 23.

This lock is applicable with obvious modifications for use on receptacles with hinged lids or tops, and the like, such as is illustrated in Fig. 8, wherein the part corresponding to the bar 18 is the part 32 and is fastened to the lid and enters the drum which is mounted in the front of the box. Only one of the plates 33 is used in this modification.

35 Having thus fully described my invention, what I claim as new and wish to secure by Letters Patent of the United States, is—

1. In a combination lock, a cylindrical drum, a circular plate revolvably mounted 40 in an end of the drum, said plate having a radial slot in its inner face, said plate also having a reduced portion entering the drum and making a close working fit therein, said entering portion being circumferentially 45 grooved, pins entering said groove to prevent

the withdrawal of the plate, and a bar entering the drum back of the plate, said bar being longitudinally movable and having a lateral lug entering the slot of the plate.

2. In a combination lock, a cylindrical 50 drum, a pair of circular plates forming closures for the ends of the drum, said plates having reduced portions entering the drum and making a close working fit therein, said entering portions being circumferentially 55 grooved, pins entering said grooves to prevent the withdrawal of the plates, the inner faces of said plates being radially grooved, a bar entering the drum and extending between the two plates, said bar having 60 lateral projections from its inner end entering the grooves of the two plates, and the outer end of the bar carrying a link.

3. In a combination lock, a cylindrical 65 drum, a pair of circular plates forming closures for the ends of the drum, said plates having reduced portions entering the drum and making a close working fit therein, said entering portions being circumferentially 70 grooved, pins entering said grooves to prevent the withdrawal of the plates, the inner face of said plates being radially grooved, said grooves terminating with semi-circular ends concentric with the plate, a bar entering the drum and extending between the two 75 plates, said bar having lateral projections from its inner end entering the grooves of the two plates, and the outer end of the bar carrying an inverted U-shaped link the ends of which are adapted to penetrate the drum 80 in the locked position of the link.

In witness whereof, I have hereunto set my hand and seal at Indianapolis, Indiana, this, 28th day of July, A. D. one thousand nine hundred and eight.

HORACE M. McDONALD. [L. s.]
